FLY TRAP.

No. 577,855.

Patented Mar. 2, 1897.

UNITED STATES PATENT OFFICE.

DATUS L. HAYS, OF MOOERS FORKS, NEW YORK, ASSIGNOR OF ONE-HALF
TO SIGNOR P. MORGAN, OF SAME PLACE.

FLY-TRAP.

SPECIFICATION forming part of Letters Patent No. 577,855, dated March 2, 1897.

Application filed June 11, 1896. Serial No. 595,188. (No model.)

To all whom it may concern:

Be it known that I, DATUS L. HAYS, a citizen of the United States, residing at Mooers Forks, in the county of Clinton and State of New York, have invented a new and useful Fly-Trap, of which the following is a specification.

The invention relates to improvements in fly-traps.

10 The object of the present invention is to improve the construction of fly-traps and to provide a simple and comparatively inexpensive device adapted to attract and trap flies and capable of enabling them to be readily destroyed after they have been captured.

15 The invention consists in the construction and novel combination and arrangement of parts hereinafter fully described, illustrated in the accompanying drawings, and pointed out in the claims hereto appended.

20 In the drawings, Figure 1 is a perspective view of a fly-trap constructed in accordance with this invention. Fig. 2 is a vertical longitudinal sectional view. Fig. 3 is a transverse sectional view illustrating the construction of the stationary trap-frame and the automatic brush for forcing the flies into the cage or receptacle. Fig. 4 is a detail perspective view of the trap-frame. Fig. 5 is a detail 25 perspective view of the automatically-operating brush.

Like numerals of reference designate corresponding parts in all the figures of the drawings.

30 35 1 designates a frame or casing receiving a spring-motor 2, which is provided with a fan-governor 3 to regulate the speed, but instead of employing a spring-motor any other suitable power may be used. The spring-motor 40 rotates a vertical shaft 4, journaled in suitable bearings and extending through the top of the frame or casing 1 and carrying a rotary frame or wheel 5, provided with a rim or band 6, which is supported by radial arms or 45 spokes 7, and the latter are secured to the shaft by means of a suitable hub 8.

The rim or band of the rotary frame or wheel is curved or corrugated at regular intervals to provide an annular series of concave faces 50 9, which are separated by radially-disposed

ridges 10. These curved or concave portions are provided with central circular depressions 11, forming bait-receptacles and adapted to receive any suitable substance for attracting flies which light on the rim or band in the 55 curved or concave portions thereof. As the wheel or frame rotates the flies are carried slowly and imperceptibly under a stationary trap-frame 12, curved to conform to the configuration of the rim or band and comprising 60 a top located above the rim or band and curved sides, between which the rim or band passes. The front of the trap-frame, which is adjustably mounted to position it properly with relation to the frame or band of the 65 rotary frame or wheel, is provided at its top with a transparent portion 13, which may be constructed in any suitable manner, such as by providing a plate of glass, mica, wire-gauze, or any analogous material which will permit 70 light to pass through it.

The flies are imperceptibly carried under the front portion of the trap-frame, and they are confined therein by the ridges at the ends of the curved or concave portions and are 75 forced upward through an opening 14 of the trap-frame into a cage or receptacle 15.

The stationary trap-frame is mounted on a rod 16, disposed horizontally and adjustably secured by a clamping-screw 7 in a horizontal 80 perforation of the adjustable standard 18. The rod is adapted to be moved longitudinally to arrange the curved sides of the trap-frame in proper position to prevent the rim or band of the rotary frame or wheel from binding 85 against them, and the adjustable standard, which is composed of telescoping sections, permits the trap-frame to be adjusted vertically to bring the ridges of the rim or band sufficiently close to the top of the stationary 90 trap-frame to prevent flies from escaping at the front of the frame by passing between the ridges and the top thereof.

When the flies arrive at the opening 14, they are caused to pass upward into the cage 95 or receptacle 15 by an automatically-operating brush 19, consisting of a plate arranged on the upper face of the rear portion of the top of the trap-frame and provided at its front with a substantially L-shaped depend- 100

ing flange 20. The brush is capable of swinging upward and downward, being preferably hinged to the trap-frame, although it may, as illustrated in the accompanying drawings, 5 loosely rest upon the trap-frame. The lower portion or lip of the L-shaped flange is curved and is adapted to rest upon the rim or band, and as the wheel or frame rotates the brush is alternately raised and lowered and is adapted 10 to brush the flies from the rim or band to prevent them from passing it and following the rotation of the rim or band and cause the flies to pass upward through the opening 14. The flies are brought to the lip or flange of the 15 brush by the rotation of the wheel, and as the brush moves upward it carries the flies with it, forcing them through the opening 14, the adjacent ridge preventing any return movement of the flies.

20 When the brush is loosely arranged on the top of the trap-frame, it is preferably provided with a notch or slot 21 to receive a projection or pin 22 of the trap-frame to prevent the rear portion of the brush from moving laterally and causing the front portion to bind. The trap-frame is provided with a transverse rod 23, located directly above the lip of the L-shaped flange and preventing the same from being accidentally thrown out of position by any sudden movement of the gearing or the like.

35 The cage or receptacle is preferably substantially spherical. It is constructed of two separable sections, and it is provided at its bottom with a metal plate having a depending front portion upon which are mounted tapering or pyramidal escape tubes or ways 24, forming passages for the flies and permitting them to escape from the trap-frame into the 40 cage. The adjacent edges of the sections of the receptacle or cage are provided with bands 25, which frictionally engage each other, whereby the sections are held together. After the receptacle or cage has received a sufficient number of flies it may be readily removed from the device and immersed in hot water or other liquid to destroy the flies, which are emptied from the trap or cage after being killed.

45 50 The plate at the bottom of the receptacle is provided with perforations and is detachably supported by posts 26.

It will be seen that the fly-trap is simple and comparatively inexpensive in construction, that it is positive and reliable in operation, and that it is capable of effectively attracting flies and of enabling the same to be readily destroyed.

Changes in the form, proportion, and minor 60 details of construction may be resorted to without departing from the principle or sacrificing any of the advantages of this invention.

What I claim is—

65 1. In a fly-trap, the combination of a rotary frame or wheel arranged horizontally and pro-

vided with an annular series of curved portions forming ridges at their ends and provided at points between their ends with bait-receiving depressions, a cage located above 70 the rotary frame or wheel, and an automatically-operating brush resting upon the curved portions of the frame or wheel and actuated by contact with the same, whereby it is moved upward and downward and is adapted to 75 brush flies from the frame or wheel and carry them upward into the cage, substantially as described.

2. In a fly-trap, the combination of a rotary frame or wheel provided with a rim having 80 an annular series of curved portions forming intervening ridges, a stationary trap-frame forming a passage for the rim of the wheel or frame and covering a portion thereof, a receptacle located above the trap-frame, and 85 an automatically-operating device capable of moving upward and downward and resting upon and actuated by the frame, whereby flies are brushed from the latter and carried upward into the receptacle, substantially as 90 described.

3. In a fly-trap, the combination of a rotary frame or wheel provided with a rim having a series of curved portions forming ridges and provided with depressions to receive a suitable bait, a stationary trap-frame conforming to the configuration and receiving a portion 95 of the frame and provided at its top with an opening for the passage of flies, a receptacle mounted on the trap-frame and having a fly- 100 entrance located over the opening of the trap-frame, a movable brush mounted on the trap-frame and having a substantially L-shaped flange located at the opening of the trap-frame and resting upon the frame and moved up- 105 and downward by the same, whereby flies are forced upward from the opening in the receptacle, substantially as described.

4. In a fly-trap, the combination of a frame, a wheel provided with a rim having an annular series of curved portions forming radial ridges, means for rotating the wheel, a stationary trap-frame conforming to the configuration and covering a portion of the rim and provided at its front with a transparent portion, said trap-frame being provided in rear of the transparent portion with an opening, a removable receptacle mounted on the trap-frame and having a fly-entrance located over the opening thereof, an automatically-operating brush consisting of a plate loosely arranged on the top of the trap-frame, and a depending L-shaped flange arranged at the opening of the trap-frame and resting upon the rim, a transverse rod mounted on the trap-frame and located in front of the L-shaped flange, and means for holding the rear portion of the plate in position, substantially as described.

5. In a fly-trap, the combination of a wheel 130 provided with a rim having a series of curved portions, a trap-frame provided with a hori-

zontal forwardly-extending rod, a standard capable of vertical adjustment and having an opening receiving the rod, means for securing the rod in the opening, a receptacle mounted on the trap-frame, and means for brushing flies from the rim and forcing them in the receptacle, substantially as described.

In testimony that I claim the foregoing as my own I have hereto affixed my signature in the presence of two witnesses.

DATUS L. HAYS.
